(57) **CLAIM**

We claim the ornamental design of a perforating gun and alignment assembly, as shown and described.

DESCRIPTION

FIG. 1 is a front, top perspective view of a perforating gun and alignment assembly showing an embodiment of our new design;

FIG. 2 is a front, bottom perspective view of the perforating gun and alignment assembly of FIG. 1;

FIG. 3 is a front elevated view of the perforating gun and alignment assembly of FIG. 1;

FIG. 4 is a rear elevated view of the perforating gun and alignment assembly of FIG. 1;

FIG. 5 is a left-side elevated view of the perforating gun and alignment assembly of FIG. 1;

FIG. 6 is a right-side elevated view of the perforating gun and alignment assembly of FIG. 1;

FIG. 7 is a top plan view of the perforating gun and alignment assembly of FIG. 1; and,

FIG. 8 is a bottom plan view of the perforating gun and alignment assembly of FIG. 1.

The broken lines consisting of dashes show an environment that forms no part of the claimed design.
